UNITED STATES PATENT OFFICE.

THEODORE C. PROUTY, OF AURORA, ILLINOIS, ASSIGNOR TO ACORN BRASS MANUFACTURING COMPANY, OF AURORA, ILLINOIS, A CORPORATION OF ILLINOIS.

SAD-IRON.

1,061,634.

Specification of Letters Patent.

Patented May 13, 1913.

Application filed February 8, 1912. Serial No. 676,199.

To all whom it may concern:

Be it known that I, THEODORE C. PROUTY, a citizen of the United States, residing at Aurora, in the county of Kane and State of Illinois, have invented certain new and useful Improvements in Sad-Irons, of which the following is a specification, reference being had to the accompanying drawings.

This invention relates to improvements in 10 sad-irons of the kind employing a reservoir for gasolene from which is generated gas by means of which the iron is heated and more particularly to that type of device wherein such reservoir is utilized as the handle of 15 the iron.

It has for its object to provide an improved arrangement of the pipe for conducting the oil from the reservoir-handle to the burner; to provide improved means for 20 shielding the said reservoir from the heat produced in the body of the iron; to provide a device having a readily-removable core; to provide improved means for locking said core in place and also for locking at the 25 same time the core-carrying base to the shell or body portion; and to improve generally the construction and operation of devices of this character.

That which I believe to be new will be 30 pointed out in the claims.

In the drawings, Figure 1 is a side elevation of my improved device; Fig. 2 is a top or plan view of the same; Fig. 3 is a horizontal section taken at line 3—3 of Fig. 4; Fig. 4 is a longitudinal, vertical section taken centrally through the device; Fig. 5 is a vertical cross-section taken at line 5—5 of Fig. 4; Fig. 6 is a detail, being a horizontal section taken at line 6—6 of Fig. 4; 40 and Fig. 7 is a detail, being a section taken at line 7—7 of Fig. 4 and showing the air inlets in the rear end of the shell or body.

Referring to the several figures of the drawings, in which corresponding parts are 45 indicated by like reference characters, 10 indicates the base, the lower face of which is, of course, to be very smooth and highly polished as usual. This base is formed hollow and its side walls converge toward each 50 other and meet at its forward end so that the

base will have the usual appearance of sad-irons generally.

11 indicates a metallic core fitting within the base 10 and conforming to the interior shape of said base. Around its upper edge 55 it is provided with a recess 12 as clearly shown in Figs. 4 and 5. The making of this recess provides a narrow space at the sides and rear of the device, between the vertical walls of the base 10 and the outer face of the 60 core 11, which is adapted to receive the lower edge of the shell or body portion herein-after described.

13 indicates the shell or body portion just mentioned, which is made of a size and 65 shape to adapt its lower edge to enter the recess 12, said lower edge of the shell or body resting on the bottom of the recess that is formed in the upper edge of the core 11. Being thus seated in this recess it will be 70 held firmly between the vertical walls of the base and the upper portion of the core. It is locked in this position by an inwardly projecting point 14 formed at the forward 75 end of the base 10, which enters a suitable opening in the shell or body 13, and at its rear end by a locking lever 15 pivoted at 16 to a short rearwardly extending lug 17 on the upper rear edge of the base 10, said lug being preferably integral with said base. 80

The engaging end of this pivoted lever 15 is adapted to be projected through a slot 15^a in the rear wall of the shell or body 13 and thus lock the shell or body at its rear end firmly to the base 10. As will be seen 85 by reference to Fig. 4 the lever also lies closely over the rear end of the core 11 and thus at the same time aids in holding that core against any possible movement. The shell or body is preferably made of a single 90 piece of sheet metal suitably stamped into the desired shape. Within the shell or body is located a large tube 18 forming the burner of the device. It is preferably of tubular shape and has openings 19 in its under part 95 for the escape of the burning gas. It is closed at its forward end but open at its rear end and suitably secured at such rear end to the rear wall of the shell or body 13. This rear open end of the tube 18 is some- 100

what enlarged, as shown in Fig. 4, and the shell or body 13, opposite this enlarged rear end of the tube, is provided with air openings 19^a, of any desired shape and number, 5 through which air may be drawn for mixing with the vapor from the oil drawn from the reservoir as hereinafter described.

20 indicates a plug in the enlarged rear end of the tube 18 which is secured in the 10 rear wall of the shell or body 13, which plug in its forward portion is provided with a small discharge passage 21 that opens at its forward end into the interior of the tube 18 and also communicates with a lateral passage (see Fig. 6) 22 that communicates with the oil supply pipe hereinafter described.

23 indicates a needle-valve adapted to control both passages 21 and 22. The stem of this valve is screw-threaded into the plug 20 15 and at its outer end is provided with an ordinary head 24.

25 indicates a shield lying in the upper portion of the shell or body 13 and fitting snugly therein. As shown it is arranged between the tube 18 and the upper wall of the shell or body and it may be secured to such shell or body in any desired manner. As shown I secure it by means of a screw 26 passing through the upper wall of the shell 20 or body. At each side of the shell or body are cut a large number of openings to permit the free admission of air to the interior of the shell or body, and they are so arranged with reference to the shield 25 that 35 the air entering through them will pass above and below such shield and thereby tend to make the shield much more effective in keeping the upper wall of the shell or body, and also the parts hereinafter described are attached thereto, from becoming unduly heated.

28 indicates a bracket suitably secured to the upper wall of the shell or body 13 and raised a considerable height above such shell 40 or body. This bracket furnishes a support for the handle of the iron, said handle consisting, in the construction shown, of an arc-shaped member 29 which is considerably higher at its forward portion than at its rear portion and a long cylindrical portion 30 which is mounted upon and suitably secured to the arc-shaped portion. This portion 30 constitutes the part that is to be grasped by the hand of the operator and is 45 arranged upon the arc-shaped member 29 so that its forward end is considerably higher than its rear end. This not only makes a conveniently arranged handle, but insures the oil that is to be used in forming 50 the gas for heating the device and which is to be stored in this hollow cylindrical portion 30, always being carried down to the discharge pipe that leads it to the burner. The portion 29 of the handle is preferably made of wood as being a good non- 55

conductor of heat, and, to further insure as much as possible the portion 30 against heating, I insert pieces of asbestos, or similar insulating material, 31 between the bracket 28 and the handle portion 29. It 70 is desirable that the gasoline should pass through a comparatively long pipe before it is discharged into the burner and I have, therefore, so constructed and arranged such pipe as to provide for a large amount thereof being located outside of the shell or body and so disposed with reference to such shell or body as not to present an unsightly appearance. This pipe—indicated by 32—is connected to, and communicates with, the 75 lower rear end of the reservoir-handle 30 immediately over the stem of the valve 23. It is brought down alongside of such stem and then wound in a series of coils 33 around such stem and is then passed through 80 a suitable opening in the upper rear portion of the shell or body 13 above the shield 25, over which it extends, to near the forward end of such shield where it is bent upon itself and brought back to near the rear end 85 of the shell or body. This looped portion of the pipe that lies above the shield is marked 34. Through a notch 35 (see Fig. 3) in the rear edge of the shield the pipe is passed down and extends forward alongside 90 of and close to the perforated portion of the burner tube 18 and near the forward portion of such burner tube is turned back and its end suitably secured to the laterally extending nipple on the block 20 (see Fig. 100 6), which nipple has in it the passage 22 hereinbefore referred to. This last loop of the pipe that extends along each side of the perforated bottom of the burner tube 18 is marked 36. By this construction it will be 105 seen that the supply pipe is made very long and that the portions 32 and 33, which are entirely outside of the shell or body, will be kept comparatively cool, that the loop portion 34 lying as it does above the shield 110 25 and subjected to the air entering the openings 27 will also be kept comparatively cool although not, of course, to the same extent as the first described portions of the pipe, while the loop 36 of the pipe will be, 115 as is desired, very much heated to vaporize the oil therein as it passes to the burner through the passages 22 and 21 that are controlled by the needle-valve 23. As clearly seen in Figs. 4 and 6 the burner tube 18, 120 at about the point where it commences to enlarge, is provided interiorly with an annular wall 37 having a central opening 38 in line with the passage 21 in the plug 20. This forces the mingled air and vapor to 125 pass more uniformly and properly into the burner tube and in effect forms of the enlarged rear end of the tube 18 a mixing chamber. In the upper forward end of the handle-reservoir 30 I form a filling opening 130

which is normally closed by a hollow screw-threaded plug 39 and which may be, as shown in Fig. 4, itself provided with a second screw-plug 40 which latter may be removed if it is desired to introduce air under pressure into the reservoir.

It is often desirable to have one weight of sad-iron at one time and another weight at another time, and by my construction I 10 provide a device that can be readily and quickly adapted for these different conditions of use, for, by having a number of different cores of different thicknesses and substituting one for the other the weight of 15 the device as a whole can be materially changed, and as each core will be made so as to extend at its edge portion up to the same height in the base as any other core, and as each core will be provided with the recess 20 12 it will be seen that the shell or body will in each instance fit properly in place so that the parts can be locked together in the manner described for the core shown without any looseness of fit. These cores, of course, 25 can be rough pieces of cast metal, needing no expensive finishing, and in addition to furnishing the desired amount of weight to the device they very quickly become very much heated from the intense heat of the 30 numerous flames issuing from the openings 19 immediately above the core, and thereby tend to maintain a proper heat in the base itself. When the shell or body is to be separated from the base the lever 15 is turned 35 so as to be disengaged from such shell or body and then the rear portion of the shell or body is to be raised sufficiently to bring it above the rear wall of the base, and then, of course, a slight backward pull will draw 40 the shell or body away from the point 14 at the forward end of the base. To again connect the parts the shell or body is moved forward over the base until such point enters the opening, at which time the rear portion 45 of the shell or body can be forced down between the base and the core and then a turning of the lever 15 will again lock the two parts rigidly together.

What I claim as my invention, and desire to secure by Letters Patent, is—

1. In a sad-iron, the combination with a shell or body and a burner therein, of an oil-reservoir attached thereto, a supply-pipe leading from the reservoir to the burner, a 55 section of said pipe being located in the upper portion of the shell or body, and a shield in said shell or body interposed between said section of pipe and the burner, said shell or body being provided with openings opposite 60 the edge of said shield.

2. In a sad-iron, the combination with a shell or body and a burner therein, of an oil-reservoir attached thereto, a supply-pipe leading from the reservoir to the burner, one 65 portion of the pipe being formed into a coil

outside of the shell or body, another portion lying in the upper part of the shell or body and still another portion lying in a lower part of the shell or body and adjacent to the said burner, and a shield interposed between the burner and that portion of the pipe lying in the upper part of the shell or body.

3. In a sad-iron, the combination with a shell or body and a burner therein, of an oil-reservoir attached thereto, a supply-pipe leading from the reservoir to the burner, one portion of the pipe being formed into a coil outside of the shell or body, another portion lying in the upper part of the shell or body and still another portion lying in a lower part of the shell or body and adjacent to the said burner, and a shield interposed between the burner and that portion of the pipe lying in the upper part of the shell or body, said shell or body having air openings in its side walls adjacent to said shield.

4. In a sad-iron, the combination with a shell or body and a burner therein which extends longitudinally of the shell or body, of an oil-reservoir attached to said shell or body, a supply-pipe leading from the reservoir to the burner, one portion of the pipe being formed into a coil outside of the shell or body, another portion located in the upper part of the shell or body and bent to form a loop, and a shield below said loop portion, and still another looped portion of the pipe being arranged below said shield and adjacent to and communicating with said burner.

5. In a sad-iron, the combination with a shell or body and a burner therein, of an oil-reservoir attached thereto, a supply-pipe leading from the reservoir to the burner, one portion of the pipe comprising a loop arranged in the upper part of the shell or body and another portion comprising a loop arranged beneath it and adjacent to and communicating with the burner, and a shield interposed between said two loop portions.

6. In a sad-iron, the combination with a shell or body and a burner therein, of an oil-reservoir attached thereto, a supply-pipe leading from the reservoir to the burner, one portion of the pipe comprising a loop arranged in the upper part of the shell or body and another portion comprising a loop arranged beneath it and adjacent to and communicating with the burner, and a shield interposed between said two loop portions, said shell or body being provided with air openings to admit the entrance of air over said shield.

7. In a sad-iron, the combination with a shell or body of a longitudinally-extending burner therein having a mixing chamber for air and gas at one end, the said chamber and burner being divided by an apertured wall, a plug in said chamber, inlet and out-

let openings in said plug, a valve for regulating the supply of fuel to said plug, a liquid fuel reservoir connected with said shell and a pipe connecting said reservoir and plug.

8. In a sad-iron, the combination with a shell or body and a burner therein, said shell or body having an air-inlet, of an oil-reservoir attached to said shell or body and 10 a supply-pipe leading from the reservoir to

the burner, a portion of such pipe being formed into a coil outside of the shell or body and opposite the said air-inlet, whereby air entering said inlet first passes through said coiled portion.
